BABY SANITARY DIAPER

William F. McGraw, Jersey City, N. J.

Application May 2, 1941, Serial No. 391,568

1 Claim. (Cl. 128—284)

This invention relates to baby sanitary diapers. An object of this invention is to provide a baby sanitary diaper made of soft paper with a seat and crotch of heavier material, the paper being designed to fit the contour of babies' bodies.

Another object of this invention is to provide a sanitary diaper of the character described, which will be sanitary, and easily disposed of when soiled, and will eliminate the use of buttons, pins and metal fasteners, and can be placed on a baby's body with little disturbance to the infant, and which can be simply and quickly applied.

A further object of this invention is to provide a sanitary diaper of the character described, which will not necessitate the use of any outer covering, and which will prevent the baby's urine or excretion from seeping through, and which when soiled can be taken from the body by pulling the same from under the body, so that it may be discarded.

Yet a further object of the present invention is to provide a durable, sanitary diaper of the character described which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention.

Fig. 1 is a front perspective view of the sanitary diaper embodying the invention, shown in position for use;

Fig. 2 is a cross-sectional view taken on line 2—2 of Fig. 1; and

Fig. 3 is a top plan view of the diaper.

Referring now in detail to the drawing, 10 designates a sanitary baby's diaper embodying the invention. The same comprises a sheet 11 made from a single blank of soft paper. Said sheet has a central crotch portion 12, from which there extends forwardly a portion 13 having outwardly extending wings 15. Extending forwardly from portion 13 is a tab 16, for the purpose hereinafter appearing.

Extending rearwardly from the crotch portion 12 is a portion 17, from which there extends wings 18 and 19. The top surface of the wing 18 is covered by adhesive material, as shown at 20. The side edges of the crotch portion 12 are

curved, as shown at 22 to fit around the insides of the baby's legs.

On top of the crotch portion 12 is placed a pad 25 of heavier absorbent material such as cotton or the like material.

In applying the diaper to the baby, the baby is placed on the diaper with his legs on opposite sides of the crotch portion 12. The front portion 13 is then folded upwardly to cover the baby's abdomen. The wing 19 is then folded forwardly to cover the portion 13. The tab 16 is then folded forwardly and downwardly to cover the wing 19. The other wing 18 is then folded over the tab 16 and wing 19 and pasted thereto by use of the adhesive 20 which may be wetted for the purpose.

When the diaper is soiled, it may be just pulled down from under the baby's body. It will be noted that holes 30 are formed on opposite sides of the crotch 12, through which the baby's legs project.

It will now be understood that the diaper may be easily applied. The heavy reinforced pad will prevent seepage through the diaper. The diaper may be disposed of after use. It will be noted that no pins, buttons or other fastening members are necessary in applying the diaper to the baby.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

A diaper comprising a single sheet of paper having a crotch portion, a portion extending forwardly from the crotch portion and adapted to be folded upwardly against the abdomen of the baby, a tab extending from said forwardly extending portion, a portion extending rearwardly from the crotch portion, and formed with oppositely extending wings, one of the wings being adapted to be folded forwardly against the forwardly extending portion, said tab being adapted to be folded downwardly over said forwardly folded wing, and said other wing being adapted to be folded forwardly over said tab and first wing, said second wing being provided with adhesive to adhere the same to said downwardly folded tab, and an absorbent pad on top of said crotch portion.

WILLIAM F. McGRAW.
